Primary Examiner — Sandra Snapp(74) *Attorney, Agent, or Firm* — Lerner, David, Littenberg, Krumholz & Mentlik, LLP(57) **CLAIM**

The ornamental design for a scent diffuser, as shown and described.

DESCRIPTION

FIG. 1 is a front perspective view of a scent diffuser according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top elevation view thereof; and,

FIG. 7 is a bottom elevation view thereof.

The broken lines illustrate elements of the scent diffuser that form no part of the claimed design.

1 Claim, 3 Drawing Sheets(56)
